PROCESS OF CRACKING HYDROCARBON OILS

Jacque C. Morrell and Gustav Egloff, Chicago, Ill., assignors to Universal Oil Products Company, Chicago, Ill., a corporation of South Dakota

Application February 8, 1930, Serial No. 426,797

1 Claim. (Cl. 196—48)

This invention relates to improvements in the art of treating hydrocarbons, and pertains in its specific embodiment to the conversion at elevated temperatures of a multiplicity of hydrocarbon materials to motor fuel of high anti-knock value and accompanying reaction products.

Among the objects of our invention is the utilization as cracking stocks of various hydrocarbon fractions having intermediate boiling point range such as heavy gasoline ends, kerosene or kerosene distillate fractions, pressure distillate bottoms, and various other cuts of products obtained in the refinery, and the processing of such materials simultaneously with heavier hydrocarbon cracking stocks or the stocks usually charged to the cracking plant in such a manner as to effect the best yield and quality of desired products. Frequently the use of such lower boiling hydrocarbon materials in the usual methods of processing is avoided because of vaporization and distillation with no substantial conversion of the intermediate stock introduced or a portion thereof. In cases of this kind such stocks usually have to be processed in special equipment. In the absence of such equipment these stocks are disposed of at small profit.

Frequently the intermediate fractions introduced will contain more or less heavy gasoline ends and which will contaminate the final product from the cracking process when the usual methods are used, so that the resulting motor fuel will not have a balanced boiling point range. In this event it becomes necessary to go to the expense of adding a low boiling blending stock such as natural or casinghead gasoline to bring the contaminated product to motor fuel specifications. Such contamination usually also results in a lowering of the anti-knock value of the final gasoline. Our invention provides a method where these objectionable features are overcome.

Among other objects of our invention is the processing of hydrocarbons which are within the motor fuel boiling point range and have poor anti-knock properties. Such oils can be introduced into our process in a similar manner as the above mentioned intermediate fractions and treated together with preferably a heavier cracking stock at conditions suitable for procuring a composite anti-knock motor fuel.

The lighter hydrocarbon oil to be processed may not necessarily be a stock obtained outside the process, but may be a product obtained within the process, as for example, the bottoms separated from end point motor fuel obtained in a secondary tower. Such towers are usually operated at lower pressure than the foregoing portion of the cracking process so that the bottoms will require pumping when they are returned to the process.

Our invention comprises in its specific embodiment, the processing of intermediate or light hy-

drocarbon oil fractions as above described by introducing same preferably directly to the oil flowing to or in the heating zone of a cracking or conversion process and subjecting the mixed oil containing also preferably heavier cracking stock previously introduced, under suitable conditions of treatment at elevated temperature in the production of a maximum of anti-knock motor fuel with a minimum of residual and gaseous products. The general principle involved is the processing of hydrocarbon oils which are likely to vaporize during pre-treatment and escape subjection to conversion treatment conditions in a direct manner and under suitable conditions so as to obtain the desired yield and products from the plurality of charging stocks.

Mixing of the various oils prior to their introduction to the cracking process as sometimes practiced does not accomplish the purpose or derive the benefits obtained in the practice of our invention, since in such practice one must of necessity depart from the method of simultaneously cracking the plurality of stocks according to our invention. The invention will be more readily understood by referring to the accompanying drawing which illustrates in a somewhat schematic and diagrammatic manner certain preferred embodiments of the process of our invention and will be described below.

Temperature and pressure conditions used in the process vary, depending upon the character of the various combinations of oil processed and the products desired, for instance, the temperature of the oil leaving the heating element on its way to the reaction zone may vary from 800° to 1200° F., more or less, and the pressure may vary from high superatmospheric pressure to atmospheric or sub-atmospheric pressure. Differential pressures may be used in the process.

Referring to the drawing, which is a diagrammatic elevational view of one type of apparatus utilized in carrying out our invention, the heavier cracking stock is introduced through line 1 and valve 2 to the suction side of the pump 3 and is pumped through line 4 and valve 5 to the dephlegmator 6 where it is preheated by heat interchange with the vapors from the cracking zone. The preheated cracking stock together with condensed vapors flow downward through line 7 and valve 8 to the suction side of the pump 9 from which they are pumped through line 10 and valve 11 to the heating element 12 located in heating zone 13. A portion or all of the oil pumped by pump 3 may flow through line 14 and valve 15 into line 10 leading to the heating element 12 by suitable adjustment and regulation of valve 5 in line 4 and valve 15 in line 14. The lighter cracking stock may be introduced through line 16 and valve 17 to the suction side of pump 18 and pumped through line 19 and valve 20 in a man-

ner and as is illustrated by its passage through line 19 with valve 21 open and valve 22 in line 23 closed, the oil entering line 10 and mixing with the flow of the heavier cracking stock and 5 reflux condensate from the dephlegmator passing to the heating element. Or a portion, or the whole flow of the lighter charging stock may be directed through line 24 and valve 25 to any suitable point in the heating element by the obvious 10 regulation and adjustment of valves 21 and 25.

The heated materials or products leave the heating element through line 26 and valve 27 and enter the reaction chamber 28 where the reaction continues and vaporization and separation 15 of non-vaporized materials occur. Materials withdrawn from this reaction zone during the period when the process is being brought to operating conditions or removed during the operation may be withdrawn through line 29 and valve 20 30 which may lead to storage or for subsequent suitable processing by means not shown. The vaporous and gaseous products leave the reaction zone through line 31 and valve 32 and enter near the bottom of the dephlegmating zone 6, where 25 the vapors may be subjected to heat interchange and/or cooling. The vapors and gases from the dephlegmator 6 pass through the line 33 and may be directed in a manner such as is illustrated by the passage of these vapors and gases through 30 line 33 with valve 34 open and valve 35 in line 36 and valve 37 in line 38 closed. The flow is then through valve 39 and the condenser and/or cooler 40 and the cooled and condensed products flow 35 through line 41 and valve 42 into the receiver 43 where separation of liquid and condensed vapors and gases is effected. The gases and uncondensed vapors leave the system through line 44, regulated by valve 45, and the liquid product containing motor fuel hydrocarbons is withdrawn 40 through line 46, regulated by valve 47. Regulated portions of the liquid product in the receiver 43 may be discharged through the line 48 and valve 49 to the suction side of the pump 50 which pumps this oil through line 51 in a manner such as is 45 illustrated by the passage through valve 52 to the top of the dephlegmator 6 with valve 53 in line 54 and valve 55 in line 56 closed.

If a secondary tower is used the vapors passing from the dephlegmator 6 through the vapor line 50 33 to the condenser and/or cooler 40 are directed as will be illustrated by the flow through line 36 with valve 35 open, valve 34 in line 33 closed and valve 37 in line 38 open. The vapors enter the lower part of the secondary tower 57 and are subjected to fractionation, the condensate flowing 55 down through line 58 and valve 59 and the fractionated vapors and gases leaving through line 38 and valve 37, and flowing to cooling, condensing and collecting means as previously described.

The distillate from the receiver 43 which is pumped by pump 50 is introduced to the top of the secondary tower through line 54 and valve 53, valve 52 in the continuation of the line 51 being closed. The reflux condensate from the secondary tower 57 flowing downward through line 58 and valve 59 may be recirculated, in part, to the dephlegmator 6, with or without cooling (cooling means not shown), by having valve 60 in line 61 closed and pumping the condensate by means of pump 62 through lines 63 and 56 with valves 64 70 and 55 open and valve 22 in line 23 closed. This condensate which is of an intermediate character may be pumped with or without cooling, in part or

in whole, by pump 62 through line 63 into the lines 23 and 19 by suitable adjustment of valves 64 and 55 in line 56, valve 22 in line 23 and valve 20 in line 19 and the flow directed to the heating element as previously described for charging the lighter charging stock. If lighter cracking stock is not introduced from an outside source when the secondary tower is used, pump 18 can be omitted. It may also be omitted when using a secondary tower except when it is desired to pump reflux condensate from the secondary tower to the top of the dephlegmator.

As a specific illustration of one embodiment of the practice of our invention and the results obtained:

A reduced Mid-continent crude oil of 20-22 A. P. I. gravity constituting 80% of the total cracking stock charged to the process is introduced into the dephlegmator of the unit. Kerosene distillate of 37-38 A. P. I. gravity derived from the same crude and constituting 20% of the total cracking stock charged to the process is pumped into the mixture of reflux condensate and heavier charging stock being pumped to the heating element. The temperature and pressure 100 on the processed materials leaving the heating element are approximately 930° F. and 250 pounds. Uniform pressure is used on the entire system. The vapors from the reaction chamber are dephlegmated and partially converted hydrocarbons 105 condensed and returned to the heating zone, the temperature at the top of the dephlegmator being maintained at 450° F. by the recirculation of pressure distillate from the receiver. The pressure on the system is regulated by maintaining the 110 liquid level in the receiver and the release of the 115 uncondensable gases formed during the operation.

The yield of lower boiling point hydrocarbons, pressure distillate so-called, is approximately 61% based on the total charging stock and contains 115 approximately 80% Navy end point gasoline.

The anti-knock value of the gasoline produced from this operation is the equivalent of 41% benzol in Pennsylvania straight run gasoline.

Our invention should not be construed as being limited to the illustrations which are shown in the drawing or in the operation cited by way of example, or to the particular plurality of charging stocks used, or to the proportions thereof, since within the scope of the operation of the process 125 of our invention many combinations of charging stock and many types of operations may be used.

We claim as our invention:

A process for simultaneously cracking heavy hydrocarbon oil and increasing the anti-knock 130 value of light motor fuel-containing distillate which comprises passing the motor fuel-containing distillate in a restricted stream through a heating zone and subjecting the same therein to cracking conditions of temperature and pressure, 135 discharging the thus heated distillate into a reaction zone maintained under cracking conditions of temperature and pressure, removing the vapors and dephlegmating the same in contact with the heavy oil to be cracked, supplying the resultant 140 mixture of heavy oil and reflux condensate to the heating zone and subjecting the same in the heating and reaction zones to the cracking conditions in admixture with said distillate, and finally condensing the dephlegmated vapors as a product 145 of the process.
